US0D1078117S

(12) **United States Design Patent** (10) Patent No.: **US D1,078,117 S**
(45) Date of Patent: ** Jun. 3, 2025

(54) **REAR COMBINATION LAMP FOR AUTOMOBILE**

(71) Applicants: **HYUNDAI MOTOR COMPANY**, Seoul (KR); **Kia Corporation**, Seoul (KR)

(72) Inventors: **Sang Min Lee**, Hwaseong-si (KR); **Kwang Duck Han**, Seoul (KR)

(**) Term: **15 Years**

(21) Appl. No.: **35/515,721**

(22) Filed: **Nov. 11, 2022**

(80) **Hague Agreement Data**

Int. Filing Date: **Nov. 11, 2022**

Int. Reg. No.: **DM/225093**

Int. Reg. Date: **Nov. 11, 2022**

Int. Reg. Pub. Date: **Dec. 9, 2022**

(30) **Foreign Application Priority Data**

Jul. 7, 2022 (KR) 30-2022-0027391

(51) **LOC (15) Cl.** **26-06**

(52) **U.S. Cl.** ..... **USPC** **D26/35**

(58) **Field of Classification Search**

USPC D26/24, 28-36, 138, 139

CPC F21S 41/141; F21S 41/20; F21S 41/18; F21S 41/00; F21S 43/14; F21S 43/00; F21S 43/10; F21W 2103/30; F21W 2103/00; F21W 2103/45; F21W 2103/35; F21W 2107/00; F21W 2107/10
